SKIVING MACHINE

William C. Card, Jr., Winthrop, Mass., assignor
to Compo Shoe Machinery Corporation, New
York, N. Y., a corporation of Delaware

Application October 19, 1934, Serial No. 748,979

19 Claims.

(Cl. 12—17)

This invention relates to the shoe manufacturing art, and more particularly to a skiving machine for making complementary insoles and outsoles of the type shown in Sbicca Patent No. 5 1,902,725.

A general object of the invention is to provide a machine which is capable of separating a piece of rounded sole stock into an insole having a perforate forepart and an outsole having a mating 10 landed portion opposite such insole perforation, wherein the separation is effected in a single skiving or splitting operation.

More particularly, the invention has for objects the provision of a skiving or splitting machine having a splitting knife cooperating with die and matrix rollers suitably shaped to form complementary insoles and outsoles of a desired configuration, wherein there is provided means for positioning and feeding leather stock with 20 reference to said rollers to assure proper registry of the work therewith.

Further objects of the invention are to provide a machine of this type which is largely automatic in its operation, is easy to operate with a minimum of effort and skill on the part of the 25 operator, is rugged, and is capable of rapidly, efficiently and accurately forming complementary insoles and outsoles of the required type.

A further object of the invention is to provide 30 a positioning mechanism for rounded sole blanks and the like which is adapted to present such blank in proper cooperative registry with an operating means designed to treat predeterminedly located portions thereof.

Other objects of the invention will in part be 35 obvious and will in part appear hereinafter.

The invention accordingly comprises the features of construction, combination of elements, and arrangement of parts, which will be exemplified in the construction hereinafter set forth and the scope of the application of which will be indicated in the claims.

For a fuller understanding of the nature and objects of the invention reference should be had 45 to the following detailed description taken in connection with the accompanying drawings, in which:

Fig. 1 is a vertical sectional view of a sole splitting machine embodying principles of the 50 present invention, taken substantially along line 1—1 of Fig. 2;

Fig. 2 is a fragmentary plan view showing approximately one-half of the machine of Fig. 1, parts thereof being broken away or shown in section better to illustrate the construction;

Fig. 3 is a fragmentary sectional detailed view showing the operation of the die and matrix pressure rollers used in the present machine;

Fig. 4 is a vertical sectional view taken substantially along line 4—4 of Fig. 1;

Fig. 5 is a vertical sectional view taken substantially along line 5—5 of Fig. 1;

Fig. 6 is a plan view of an insole produced during operation of the present machine;

Fig. 7 is a plan view of a similarly formed outsole; and

Fig. 8 is a fragmentary perspective view on an enlarged scale showing details of a side gage construction.

The above mentioned Sbicca Patent No. 1,902,725 shows a complementary insole and outsole unit which is adapted to be cut from a single piece of sole leather stock having the combined thickness of the insole and outsole. It is the purpose of the present invention to provide a machine capable of forming such insole and outsole combinations in a single splitting operation. The products of the present machine, for example, are shown in Figs. 6 and 7. They comprise an outsole 10 having a raised land 11 at its 25 central forepart portion, together with an insole 12 which is split off from such outsole and has its central forepart portion centrally perforate as at 13 so as to correspond and interfit with the land 11.

Referring to the drawings, the machine for providing such sole parts comprises a base 14, at the opposite sides of which are upright standards 15 and 16 joined at their upper ends by a rigidifying strut 17.

A splitting knife 18 is mounted on the upper side of base 14, longitudinal adjustment thereof being provided by means of adjustment screws 19 which are workable in conjunction with its slotted mounting at 20.

An upper pressure roll 21 and a lower pressure roll 22 are provided for passing work stock to the knife 18 in position to be split thereby. The upper pressure roll is mounted on and fixed for rotation with a shaft 23 (Fig. 5), the ends of 45 which are rotatable in slidably journals 24 and 25. The upper sides of these journals are each provided with a dovetail inclined wedge slot 26 with which a pair of similar blocks 27 are adapted to cooperate to vary the vertical position of the upper roll 21 with reference to the knife 18.

Each block 27 has affixed to its inclined underside a wedge block 28 which is wider than block 27 so as to fit in dovetail fashion in corresponding slot 26, whereby lateral movement of block 55

27 will effect vertical movement of the journals 24 and 25, these latter being slidably mounted in suitable guideways on their respective standards (Fig. 2). Lateral movement is imparted to blocks 5 27 by means of a rod 29 which is freely rotatable in a journal 30 affixed to the machine frame. This rod has threaded portions 31 and 32 which work respectively in threaded openings in blocks 27. Rod 29 is adapted to be rotated by a hand 10 wheel 33, turning of which effects lateral movement of the wedge blocks and vertical movement of the roller journals. The extent of this movement is indicated by some suitable mechanism, such as a pointer 34, which is rotatably journaled in a casting 35 affixed to the strut 17, and has a link 36 extending between its lower end and an integral projection 37 on one of the wedge blocks 27. This pointer is adapted to play over a scale suitably calibrated to indicate the number 15 of irons thickness between the edge of knife 18 and the underside of the upper roll 21.

The lower pressure roll 22 is fixed for rotation with a drive shaft 38, the ends of which are rotatable in journals 39 and 40 which are guided 25 and vertically slidably in standards 15 and 16 respectively. Compression springs 41 act normally to urge standards 39 and 40 upwardly so that roll 22 tends to approach roll 21. Intermeshing gears 42 and 43 are respectively movable with 30 shafts 23 and 38 and provide for related driving movement of the pressure rolls.

Shaft 38 is driven by any suitable power mechanism through the medium of a one-revolution clutch generally indicated at 44. This clutch may 35 have any suitable or conventional construction.

The end pressure roll 22 is provided with a pair of laterally placed dies such as 45 which are removably and replaceably affixed by means of screws. The upper pressure roll 21 has a detachable section 46 screwed thereto, in which are 40 located matrices 47 corresponding to and located in opposed registry with dies 45. Each die 45 and its corresponding matrix 46 are suitably configured so as to flex the sole stock located in the 45 outsole land area 11 up out of the way of the splitting knife 18 during passage of the sole stock between the rolls, as is shown in Fig. 3. One die and matrix is designed to treat right sole units and the other is configured for left sole units, it being intended that a pair of sole combinations may be worked upon during each 50 operation of the machine. Dies and matrices of different sizes and configurations may be used when wanted by virtue of their removable mountings on the pressure rolls.

55 The work stock that is to be presented to the above described flexing and splitting mechanism comprises a previously rounded blank of sole leather stock having the combined thickness of the ultimately formed insole and outsole.

60 Means are provided for positioning such rounded sole stock in proper registry with respect to the die and matrix on the pressure rolls so that the land 11 and perforation 13 will be formed in the proper part of their respective soles as the stock 65 is passed through the machine. This positioning means is associated with a work holding table 48 which is fixed to and extends from casting 14 toward the operator, who stands facing the machine as the latter is viewed in Fig. 4. An end 70 gage 49 is slidably mounted on table 48 for longitudinal adjustment with respect thereto, such adjustment being effected by means of a rack 50 and pinion 51, which latter is controlled by a 75 suitably calibrated hand wheel 52. The longi-

tudinal position of the sole stock with reference to the die and matrix is determined by abutting its toe end against this end gage. One gage 49, with its appurtenant parts, is provided at each side of the machine for the respective right and left 5 soles. The lateral position of the sole stock is controlled by means of side gages 53 and 54 which are respectively mounted on bent arms 55 and 56, which are pivoted at their lower ends to a strap 57, forming a fixed part of the machine 10 frame. Each arm 55 is meshed with its corresponding arm 56 by means of suitable gears 58, and a spring 59 reacts between each arm 55 and an adjoining portion of the machine frame so as to give the gages 53 and 54 a normal bias toward each other in a centered position. Work stock held against gage 49 is automatically laterally centered with reference to the die and matrix by the described centering side gage construction. 15 20

Means are provided for facilitating the insertion of work in the several described gages and also for holding it in position, once it has been located, against slippage with reference to the die and matrix during its movement through the 25 machine. Such means includes a pair of opposed preliminary gripping or feed rollers, comprising an upper roller 60 and a lower roller 61, which are adapted to clamp down upon the work and grip it between them when it has been positioned by 30 means of gages 49, 53 and 54. The upper roller 60 has its ends journaled in arms 62 and 63 which are mounted for oscillatory movement on upper roll shaft 23. A spring 64 which is anchored to pin 65 on the main frame (Fig. 4) 35 pulls arm 63 downwardly, thus giving roller 60 a normal bias toward roller 61. The latter roller is similarly mounted on arms such as 66 (Figs. 1 and 2), which are oscillatably mounted on lower roll shaft 38. A spring 67 reacts between 40 arm 66 and a bridge casting 68 forming part of the base 14, such spring permitting yielding movement of arm 66 downwardly when needed. A support or table section 69 (Figs. 1 and 2) spans arms 66 and affords a support for the work as 45 it passes from rollers 60 and 61 to the main pressure rolls.

The upper roller 60 is connected for feeding movement with upper roll 21 by means of a gear 70 on shaft 23 which meshes with an idler 71 50 mounted on arm 62, which in turn meshes with a gear 72 which is movable with roller 60. The position of gears 71 and 72 have been indicated by dotted lines in Fig. 1, although actually they are mounted on arm 62 as is best shown in Fig. 55 4. A similar gear train, comprising a driving gear 73, an idler 74 and a driven gear 75, serves to rotate the lower preliminary roller 61. The several gears are so arranged that the peripheral or surface speeds of upper roller 60 and upper 60 roll 21 are the same, and this is also the case with lower roller 61 and lower roll 22, so that work is adapted to be positively fed between the rollers and rolls in an even manner without any 65 tendency to buckle or drag.

The upper roller 60 is adapted to be separated or spaced from lower roller 61 during insertion of the work in the positioning gages. The means for doing this comprises a pin 76 (Figs. 1 and 8) 70 which extends downwardly from arm 63 and rides on the surface of a cam 77 which is fixedly mounted on a transverse shaft 78. This shaft has an operating handle 79 whereby it is adapted to be oscillated through approximately a one-quar- 75

ter turn during the sole positioning and gripping operation.

Means also are associated with this shaft 18 to control the side gages 53 and 54 during insertion 5 of the work with a view first to spacing such gages slightly while the rollers 60 and 61 are spaced to permit the heel end of the sole blank readily to be slipped therebetween; next, to allow such side gages to act under the influence of their springs 10 59 to center the work; and finally, upon additional movement of shaft 18, to permit lowering of roller 60 upon roller 61 while retracting side gages 53 and 54 from the work so as to permit its passage therebetween without interference 15 therefrom once the proper position of registry has been determined. The structure for effecting this includes an additional cam 80, fixed on shaft 18, which has a high portion 81 (Figs. 1 and 8) which, when handle 79 is in upright position, is 20 adapted to ride over and depress the inner end 82 of a U-shaped plunger 83, which is mounted for vertical sliding movement between strap 57 and bridge 68. The plunger may be laterally confined for vertical movement only in any suitable manner, as, for example, by a pair of vertical 25 confining ribs spaced on either side thereof, and located on the bridge 68, one of such being shown at 68' in Fig. 1. The outer arm of this plunger terminates at 84 and intermediate its length this 30 arm carries a fixed collar 85 which overhangs the ends of levers 86 (Figs. 4 and 8) which extend from the respective side gage arms 55. It will be seen that depression of plunger 83 will cause collar 85 to engage levers 86 and effect retraction 35 or spreading movement of the side gages 53 and 54. Thus, as the cam projection 81 rests upon the plunger at 82, there is sufficient depression of such plunger to effect enough retraction of gages 53 and 54 to facilitate insertion of the heel end of 40 the sole blank therebetween. While cam projection 81 is in this gage retracting position, a high portion of cam 77 underlies pin 76 so that the rollers 60 and 61 are separated. Upon slight further rotation of shaft 18 in a clockwise direction 45 (Fig. 1), the cam projection 81 leaves the inner end of plunger 83 and permits springs 59 to actuate the side gages which mutually approach and grasp the sole blank adjacent its shank portion so as to center it with reference 50 to the end gage 49 and with reference to the die and matrix on the pressure rolls. Still further clockwise rotation of shaft 18 eventually brings the lowermost portion of cam 77 beneath pin 76, as shown in Fig. 8, thus permitting roll 60 to descend upon the work and in conjunction with roller 61, to grip the work and hold it in its adjusted position. At the same time a finger 87 on cam 80 55 abuts and depresses the outer end 84 of the plunger 83, and this depression of the plunger again serves widely to retract side gages 53 and 54 so that the wider forepart portion of the sole may pass therebetween without interference therefrom. At this stage the handle 79 is in approximately horizontal position and the work is fixedly 60 clamped between rollers 60 and 61 with its toe end against gage 49 and with side gages 53 and 54 drawn well out of its path.

The work is then ready for movement through the machine, this being effected by throwing the 65 one-revolution clutch into driving connection with roll shaft 38. Through their associated gearing, rotation of such roll effects driving and feeding rotation of upper roll 21 and of the preliminary rollers 60 and 61 which begin to advance 70 the work toward and between the pressure rolls.

As the work advances between the pressure rolls it is split by knife 18, and the upper portions of its forepart are flexed by the die and matrix structure so as to form the desired landed and perforated portions on the outsole and insole. 5

The operation of the machine is more or less apparent from the foregoing description. It will be seen that with the parts at rest as shown in Fig. 1, the operator sees that handle 79 is in upright position, at which time the preliminary 10 rollers will be spaced and the side gages will be slightly retracted. The operator then slips the heel end of both the right and left blank between the rollers 60 and 61 and between their appropriate side gages 53 and 54 until their toe ends 15 abut their respective end gages 49. The lever 79 is then pulled toward the operator and during rotation of shaft 18 the side gages automatically center the two soles, such gages being later retracted through the operation of cam finger 87 20 as the preliminary gripping rollers 60 and 61 clamp the work to hold it in its adjusted position. Upon power being applied to the pressure rolls for a single revolution thereof, the soles are fed entirely through the machine and split in the 25 required manner in a single splitting operation.

It will be seen that there has been provided a machine which is well suited to fulfill its intended functions. Since certain changes may be made in the above construction and different embodiments of the invention could be made without departing from the scope thereof, it is intended that all matter contained in the above description or shown in the accompanying drawings shall be interpreted as illustrative and not 30 in a limiting sense. 35

It is also to be understood that the following claims are intended to cover all of the generic and specific features of the invention herein described, and all statements of the scope of the 40 invention which, as a matter of language, might be said to fall therebetween.

Having described my invention, what I claim as new and desire to secure by Letters Patent is:

1. A splitting machine for sole stock comprising 45 a splitting knife, opposed rolls for passing stock to said knife, a die on one of said rolls and a matrix on the other, said die and matrix being configured to flex said stock so as to cause said knife to form a landed area in the central forepart portion of one split section thereof, and to form a complementary area in the forepart portion of the other split section thereof, positioning means for engaging said stock to present it to said rolls in proper registry with said die and matrix, clamping means engageable with said stock to maintain said registry during feeding movement of the stock, connections between said positioning means and said clamping means for spacing the latter while the former operates and 50 for retracting the positioning means while the clamping means operates, and means for driving 55 said rolls.

2. A splitting machine for rounded sole stock comprising a splitting knife, opposed rolls for 60 passing said stock to said knife, a die on one of said rolls and a matrix on the other, a work support associated with said rolls, positioning means for locating said stock on said work support in position to register with said die and 65 matrix, means for clamping said stock in its registered position and for advancing it to said rolls, and driving means for said rolls.

3. A splitting machine for rounded sole stock comprising a splitting knife, opposed rolls for 70

passing said stock to said knife, a die on one of said rolls and a matrix on the other, a work support associated with said rolls, positioning means for locating said stock in proper registry with said die and matrix including an end gage fixed on said support and side gages movable into engagement with the opposite sides of the stock, clamping means engageable with said stock to maintain said registry during movement of said stock toward said rolls, means for retracting said side gages from engagement with said stock during such movement, and driving means for said rolls.

4. A splitting machine for rounded sole stock comprising a splitting knife, opposed rolls for passing said stock to said knife, a die on one of said rolls and a matrix on the other, a work support associated with said rolls, an end gage on said support for determining the longitudinal position of said stock with respect to said rolls, spring biased movable side gages for positioning said stock laterally with respect to said rolls, clamping means engageable with said stock to maintain said registry during movement of said stock toward said rolls, means associated with said clamping means for retracting said side gages while said clamping means holds said stock, and driving means for said rolls.

5. A splitting machine for rounded sole stock comprising a splitting knife, opposed rolls for passing said stock to said knife, a die on one of said rolls and a matrix on the other, positioning means for locating said stock in proper registry with said die and matrix, opposed preliminary rollers for gripping said stock when it is positioned, and driving means for said rolls.

6. A splitting machine for rounded sole stock comprising a splitting knife, opposed rolls for passing said stock to said knife, a die on one of said rolls and a matrix on the other, positioning means for locating said stock in proper registry with said die and matrix, opposed preliminary rollers adapted to grip said stock when it is positioned, means separating said rollers while said stock is being positioned, and driving means for said rollers.

7. A splitting machine for rounded sole stock comprising a splitting knife, opposed rolls for passing said stock to said knife, a die on one of said rolls and a matrix on the other, positioning means for locating said stock in proper registry with said die and matrix, opposed preliminary rollers adapted to grip said stock when it is positioned, and means for driving said rolls and rollers.

8. A splitting machine for rounded sole stock comprising a splitting knife, opposed rolls for passing said stock to said knife, a die on one of said rolls and a matrix on the other, positioning means for locating said stock in proper registry with said die and matrix, opposed preliminary rollers adapted to grip said stock when it is positioned, and means for driving said rolls and rollers at substantially the same surface speed.

65 9. A splitting machine for rounded sole stock comprising a splitting knife, opposed rolls for passing said stock to said knife, a die on one of said rolls and a matrix on the other, positioning means for locating said stock in proper registry with said die and matrix, opposed preliminary rollers adapted to grip said stock when it is positioned, gearing between one of said rolls and the corresponding roller for moving them in the same direction at substantially the same surface speed, and means for driving said roll.

10. A splitting machine for rounded sole stock comprising a splitting knife, upper and lower rolls for passing said stock to said knife, a die on one of said rolls and a matrix on the other, positioning means for locating said stock in proper registry with said die and matrix, upper and lower preliminary rollers adapted to grip said stock when it is positioned, gearing between said upper roll and roller, gearing between said lower roll and roller, said gearing being arranged to drive the corresponding rolls and rollers in the same direction at substantially the same surface speed, and means for driving said rolls.

11. A splitting machine for rounded sole stock comprising a splitting knife, opposed rolls for passing said stock to said knife, a die on one of said rolls and a matrix on the other, positioning means for locating said stock in proper registry with said die and matrix, opposed preliminary rollers, spring means urging said rollers into gripping relation with said stock when it is positioned, means having connections with said positioning means for separating said rollers while said stock is being positioned, and means for driving said rolls.

12. A splitting machine for rounded sole stock comprising a splitting knife, opposed rolls for passing said stock to said knife, a die on one of said rolls and a matrix on the other, positioning means including retractable side gages for locating said stock in proper registry with said die and matrix, opposed preliminary rollers, spring means urging said rollers into gripping relation with said stock when it is positioned, means for retracting said side gages when said rollers grip the stock, and means for driving said rolls.

13. A splitting machine for rounded sole stock comprising a splitting knife, opposed rolls for passing said stock to said knife, a die on one of said rolls and a matrix on the other, positioning means including retractable side gages for locating said stock in proper registry with said die and matrix, opposed preliminary rollers, spring means normally urging said rollers toward each other, means for spacing said rollers while said stock is being positioned, said spacing means being movable to permit said rollers to grip said stock when it is positioned, means for retracting said side gages when said rollers grip the stock, and means for driving said rolls.

14. A splitting machine for rounded sole stock comprising a splitting knife, opposed rolls for passing said stock to said knife, a die on one of said rolls and a matrix on the other, positioning means including opposed side gages spring biased toward each other for locating said stock in proper registry with said die and matrix, opposed preliminary rollers spring biased toward each other, means for spacing said rollers and retracting said side gages to permit insertion of said stock therebetween, said means being movable to permit engagement of said side gages with the stock while holding said rollers spaced, and being further movable to permit said rollers to grip said stock and again to retract said side gages, and means for driving said rolls.

15. A splitting machine for rounded sole stock comprising a splitting knife, opposed rolls for passing said stock to said knife, a die on one of said rolls and a matrix on the other, positioning means including opposed side gages spring biased toward each other for locating said stock in proper registry with said die and matrix, opposed preliminary rollers spring biased toward each other, a plunger engaging said side gages to effect

retraction thereof, a cam shaft having cam means thereon associated with said rollers and said plunger, said cam means being arranged during rotation of said cam shaft first to space said rollers and retract said side gages, then to permit relative approach of said side gages while holding said rollers spaced, and then to permit relative approach of said rollers while retracting said gages, and means for driving said rolls.

10 16. In a device for operating on a predetermined area of a rounded blank of sole stock, operating means, and positioning means for said stock including an end gage, pivotally mounted side gages interconnected for mutual approach

15 and retraction, means for clamping the work in adjusted position and for feeding it to said operating means, and means for spacing said clamping means to permit insertion of the work in said positioning means.

20 17. In a device for operating on a predetermined area of a rounded blank of sole stock, operating means, and positioning means for said stock including pivotally mounted side gages interconnected for mutual approach and retraction, means for clamping the work in adjusted position, and connections between said clamping means and side gages adapted to retract said gages to permit passage of said stock therebetween when said clamp is operative.

25 30 18. In a device for operating on a predetermined area of a rounded blank of sole stock, operating means, a work support adjacent said op-

erating means, positioning means for registering said stock with respect to said operating means including, movable side gages for engaging work on said support, said side gages being interconnected for relative approach and retraction, 5 spring means tending normally to center said side gages, clamping means for maintaining said blank in such registry, and cam means associated with said side gages and clamping means, said cam means being adapted in one position to re- 10 tract said side gages and space said clamping means to facilitate insertion of work therebetween, and in another position to permit said side gages to engage and center such work.

15 19. In a device for operating on a predetermined area of a rounded blank of sole stock, operating means, a work support adjacent said operating means, an end gage on said work support, movable side gages for engaging work on said support, said side gages being interconnected 20 for relative approach and retraction, spring means tending normally to center said side gages, and cam operated means associated with said side gages, said cam operated means being adapted in one position to retract said side gages to facilitate 25 insertion of work therebetween, in another position to permit said side gages to engage and center such work, and in another position to retract said gages sufficiently to permit longitudinal movement of the work therebetween. 30

WILLIAM C. CARD, JR.
